UNITED STATES PATENT OFFICE.

HARRY ELLWOOD SLOAN, OF PITMAN, NEW JERSEY.

CIRCULAR-SAW SHARPENER.

Application filed July 24, 1923. Serial No. 653,430.

To all whom it may concern:

Be it known that I, HARRY ELLWOOD SLOAN, a citizen of the United States, residing at Pitman, county of Camden, and 5 State of New Jersey, have invented a certain new and useful Improved Circular-Saw Sharpener, of which the following is a specification.

This invention generally stated, relates 10 to a saw-filling device and has more especial relation to a portable device of this character for sharpening circular-saws of varying diameter.

The leading object of the present invention 15 may be said to reside in the provision of a circular-saw sharpener of simple, efficient and portable design, capable of attachment to a bench, table or wall; which may be clamped in a vise or capable of standing 20 upon feet furnished for the purpose. A further object is to provide a free-running file-carriage, pivotally supported, the file-holder of which may be shifted to cant transversely the file for securing various angles. 25 A still further object is to provide means for securing varying depths of file-cuts in an efficient and convenient manner. Provision is also made for taking care of varying sizes of arbor holes as occur in different 30 makes of circular-saws. Other and further objects not at this time appearing will be set forth hereinafter.

The invention consists of the improvements 35 hereinafter described and finally claimed.

The nature, characteristic features and 40 scope of the invention will be more fully understood from the following description taken in connection with the accompanying drawings forming part hereof, and in which:

Fig. 1, is a view in front elevation of a circular-saw sharpener embodying features of the invention.

Fig. 2, is a view in section taken upon 45 the line 2—2 of Fig. 1,

Fig. 3, is a view in plan of my improved device, with the file-carriage removed, and

Figs. 4 and 5, are views showing details 50 for securing saws to place.

For the purpose of illustrating my invention I have shown in the accompanying drawings one form thereof which is at present preferred by me, since the same has been found in practice to give satisfactory and reliable results, although it is to be under-

stood that the various instrumentalities of which my invention consists can be variously arranged and organized and that my invention is not limited to the precise arrangement and organization of the instrumentalities as herein shown and described.

Referring now to the drawings, the device contemplated by the present invention, generally stated comprises an elongated, stationary, saw-holder and a reciprocating 60 pivotal file-carriage for travel thereover.

The saw-holder comprises a pair of stationary end pieces 10—11 connected by an elongated web 12, the end pieces projecting forwardly from said web as best seen in Fig. 70 3. The end pieces are each provided with corresponding portions with a vertical line of holes 13, said holes being in register, horizontally considered, to adjustably accommodate a saw-carrier in the form of a 75 shaft 14 for rotatably receiving a circular-saw 15. For illustrative purposes a saw of small diameter is shown. Saws of larger diameter may be accommodated by shifting shaft 14 to openings 13 in a lower plane. 80 The saw-carrier may be secured to a bench, table or wall, the web 12 being provided with bolt or receiving openings 16 for the purpose. If desired feet 17 may be furnished with the saw-carrier so that the device may be positioned upon a bench or table 85 without clamping means, or if desired the device may be held between the jaws of a bench-vise. The device is thus portable and convenient for use under varying 90 conditions. The saw-carrier is of substantial structure, as cast iron. With reference now to the file-carriage and its complemental file-holder it is to be noted that the former has pivotal relation with respect to and is 95 movable endwise with relation to the saw-carrier and that the latter (file-holder) is tilttable laterally of the holder. The file-carriage comprises an elongated plate 18 having extensions 18'—18'' at the ends 100 thereof and has fixed relation with an endwise movable rod 19, best seen in Fig. 2, which rod is afforded longitudinal movement through openings in end-pieces 10—11 and also is capable of movement about its 105 longitudinal axis so that the file-carriage may be afforded pivotal as well as a sliding movement. In order to provide a free-running movement for said carriage, the under side thereof is calculated to track 110

upon a roller 20, best seen in Fig. 2. The roller 20, is journaled in a vertically adjustable slide 21 mounted in end-piece 11 of the saw-carrier. It is adjustable by means of set screw 22 and lock-nut 23 so that the file-holder 24, carried by said file-carriage, may be moved toward or away from the teeth of saw 15, by reason of pivotal connection of the carriage. The file-holder 24 is movably supported between parts 18' and 18'' of the file-carriage. At each end the file-holder is provided with a screw-threaded socket extended longitudinally of the holder. At one end a bolt 25 is passed through extension 18' to cooperatively engage in said socket and at its other end the screw-threaded portion of a handle 26 is passed through extension 18'' to cooperatively engage the other of said sockets. Thus by loosening of bolt 25 and handle 26 the file-holder 24 may be moved about its longitudinal axis to tilt or cant a file 27 transversely to cut a desired pitch of saw tooth. The file-holder is designed to accommodate conventional or stock types of files and the latter may be secured to the underside of the holder by means of conventional clamps 28 of which two are usually employed. In order to prevent chattering and afford a backing or support for a saw immediately below the file, I employ a gauge 29 provided with an adjustable stop in the form of a set-screw 29'. The stop parallels the file-holder and the inner face of saw 15 is adapted to abut against said stop, as shown in Fig. 1, during a saw sharpening period. The gauge is provided with a slotted arm 30 adjustable with respect to end-piece 11 of the saw-holder by means of a set-screw 31. Thus by adjusting the gauge to proper position, circular-saws of varying size may be accommodated. To accurately adjust the file-holder to secure desired depth of file-cut, adjustment of slide 21 is effected to raise or lower the free end of file-carriage about its pivot connection. It will be noted in the connection that slide 21 carrying roller 20 has connected between it and end-piece 11, a coiled spring 32. The slide is thus under spring tension during periods of adjustment. With a saw, file-carriage, file and gauge in proper position as clearly shown in Fig. 1, reciprocation of the carriage by means of handle 26 causes the file 27 to remove the necessary amount of metal from a tooth of the saw to sharpen same. While the operator employs one hand for moving the carriage he uses his other hand in rotation of saw 15 upon shaft 14 so that each and every tooth may be sharpened without further adjustment of parts. Unskilled persons may efficiently sharpen saws by the use of the present device. Rod 19 is provided with stops 33 and 34 to limit forward and rearward move-

ment of the file carriage. These stops are made of fibre in order to soften the impact of file-carriage with the saw-holder.

Provision is necessary, with respect to saw-carrier 14, to take care of different sizes of arbor openings in circular saws. In Fig. 4, the end of saw-carrier 14 supported in end-piece 11 is shown as having a collar 35 which in connection with collar 36 (see Fig. 3) functions to prevent end-wise movement of the saw-carrier 14. Projected from said collar 35 is a short section of shaft designated 37 for receiving saws having small arbor openings. A washer 38 is then fitted over the part 37 and a screw 38' secured to place to clamp saw between said washer and collar. If a saw having a larger arbor opening is used one of the interchangeable bushings 39, shown in Fig. 5, is fitted over the end 37 of shaft 14 and a saw fitted to the flanged part 40 of said bushings. The washer 38 and screw 38' are then fitted to place so that in this instance the saw is clamped between the bushing surface and said washer.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

1. A device of the character stated comprising a stationary saw-holder including an elongated, horizontally disposed web supporting a pair of end pieces, a horizontally disposed shaft supported in said end pieces, a file-carriage having pivotal relation with the saw-holder and capable of reciprocating movement along said saw-holder and means for detachably securing a file to said carriage.

2. A device of the character stated comprising an elongated, stationary saw-holder for rotatably accommodating a circular-saw, a file-carriage having pivotal relation with the saw-holder and capable of reciprocating movement along said saw-holder, a roller interposed between said holder and carriage upon which the unsupported portion of said carriage travels and means for detachably securing a file to said carriage.

3. A device as described in claim 2, characterized by means for adjusting said roller toward or away from said carriage.

4. A device as described in claim 2, characterized by a slide under spring tension

vertically movable with respect to the saw-holder to which slide said roller is secured.

5. A device of the character stated comprising an elongated, stationary saw-holder for rotatably accommodating a circular-saw, a saw carried by said holder, a file-carriage pivoted to said holder, a file-holder, a file secured thereto, means for adjusting the free end of said carriage toward said saw-holder and a gauge adjustably carried by said saw-holder against which the inner face of said saw abuts.

6. A device as described in claim 5, characterized by means for moving the file-holder about its longitudinal axis.

7. A device of the character stated comprising a longitudinal web terminating at each end in a laterally disposed extension each apertured to receive a saw-holder, a saw-holder comprising a fixed shaft carried by said extensions one of which is shaped and proportioned to accommodate circular-saws having varying arbor openings and means for clamping a saw with respect to said shaft.

8. A device as described in claim 7, characterized by interchangeable bushings for attachment upon said shaft to receive saws having varying arbor openings.

30 9. A device of the character stated comprising a stationary saw-holder including an elongated, horizontally disposed web supporting a pair of end pieces, a horizontally disposed shaft supported in said end pieces; a file-carriage having pivotal relation with the saw-holder and capable of reciprocating movement along said saw-holder, a roller in-

terposed between said holder and carriage upon which the unsupported portion of said carriage travels, and means for detachably securing a file to said carriage.

10. A device of the character stated comprising a stationary saw-holder including an elongated, horizontally disposed web supporting a pair of end pieces, a horizontally disposed shaft supported in said end pieces, a file-carriage having pivotal relation with the saw-holder and capable of reciprocating movement along said saw-holder, a roller interposed between said holder and carriage upon which the unsupported portion of said carriage travels, a slide mounted upon one of said end pieces for supporting said roller, and means for detachably securing a file to said carriage.

55 11. A device of the character stated comprising a stationary saw-holder including an elongated, horizontally disposed web supporting a pair of end pieces, a horizontally disposed shaft supported in said end pieces, a file-carriage having pivotal relation with the saw-holder and capable of reciprocating movement along said saw-holder, a roller interposed between said holder and carriage upon which the unsupported portion of said carriage travels, a slide mounted upon one of said end pieces for supporting said roller, means for vertically adjusting said slide, and means for detachably securing a file to said carriage.

60 In testimony whereof, I have hereunto signed my name.

HARRY ELLWOOD SLOAN.
